DESIGN FOR A DOLL

John H. Granger, New York, N. Y.

Application January 11, 1939, Serial No. 82,287

Term of patent 3½ years

To all whom it may concern:

Be it known that I, John H. Granger, a citizen of Hungary, residing at New York city, State of New York, 24 West 68th Street, have invented a new, original, and ornamental Design for Dolls, of which the following is a specification, reference being had to the accompanying drawing, forming part thereof.

The accompanying drawing shows a perspective view of the doll embodying my design.

The other side of the doll design is substantially the same as illustrated except that the head portion is unornamented.

I claim:

The ornamental design for a doll, substantially as shown and described.

JOHN H. GRANGER.
